MACHINE FOR TREATING GRAVEL, SAND
AND LIKE MATERIALSWilliam L. Wettlaufer, Buffalo, N. Y., assignor to
The W. S. Tyler Company, Cleveland, Ohio, a
corporation of Ohio

Application August 19, 1933, Serial No. 685,862

7 Claims. (Cl. 209—12)

This invention relates generally to a machine for washing and scrubbing sand, gravel, stone and like materials, and more particularly to means for simultaneously effecting the grading 5 and separating of the scrubbed and washed material.

One of its objects is the provision of a machine of this character for not only thoroughly and expeditiously washing and scrubbing the material by imparting thereto a positive tumbling or cascading and volcanoing-like motion, but at the same time providing simple means for effectually grading or screening the cleaned material by the gyratory motion imparted to the 15 machine-body for producing the tumbling-like motion to the material being cleaned.

Another object of the invention is to provide a simple and inexpensive arrangement of scrubbing and screening means.

Other features of the invention reside in the construction and arrangement of parts herein-after described and particularly pointed out in the appended claims.

In the accompanying drawings:—

Figure 1 is a central longitudinal section of a scrubbing machine embodying my improvements. Figure 2 is a cross section thereof taken substantially in the plane of line 2—2, Figure 1. Figure 3 is a view similar to Figure 2 showing a 30 different arrangement of grading decks. Figure 4 is a view similar to Figure 2 showing a modified arrangement of grading decks. Figure 5 is a view similar to Figure 1 showing a still further modification of the grading decks.

Similar characters of reference indicate corresponding parts throughout the several views. In connection with the invention, a vibratory or shaking body is provided which may be of any suitable construction, that shown in the drawings,

by way of example, being adapted to gyrate in a vertical plane and consisting of end walls or plates 10, 10 between which are arranged one or more substantially trough-shaped scrubbing decks 11 for the material to be washed 40 or scrubbed. This gyrating body is disposed in a substantially horizontal position between suitable beams 12 and is balanced or supported for rotating vibratory movement on a rotary shaft 13 journaled in suitable bearings 14 applied to the beams 12. This shaft constitutes the drive 45 element of the machine and imparts to the body a positive gyratory movement, and to this end the shaft has eccentric portions 15 adjacent its ends journaled in roller or like bearings 16 attached to the end walls 10 of the gyrating body,

For the purpose of maintaining the machine in proper balance, the shaft 13 is provided with counter balanced wheels 17.

While any number of scrubbing decks 11 may be employed, I have, by way of example, shown two which are disposed side by side in parallel relation, the material to be scrubbed, cleaned and washed being delivered thereto by any suitable means at one end thereof, and being discharged therefrom after the scrubbing and washing action through a discharge passage 18 disposed in the opposite end of each scrubbing deck. As shown in Figure 2, each scrubbing deck has an inner section or shell 19 spaced from the surrounding walls thereof, which provides a 15 roughened surface for imparting to the material a tumbling-like action in response to the gyrating motion of the screen body. During the scrubbing action water is sprayed over the decks in any appropriate manner and the wash water 20 and the foreign or removed material passes through the screen section 19 into the bottom of the trough, from which it is discharged through openings 20 arranged in the bottom side of the scrubbing deck.

Arranged within each scrubbing deck 11 are a plurality of control baffles or partitions 21, 22 which are disposed in spaced relation lengthwise of the deck and are arranged to direct and guide the material in a substantially spiral-like course 30 through the scrubbing decks in response to the gyrating motion of the machine body. This action serves to break up and dislodge any foreign matter from the material being scrubbed. In connection with these control baffles, which 35 no part of my present invention, reference may be had to my pending United States application for patent, Serial No. 656,275, filed February 11, 1933.

Simultaneously with the scrubbing and washing treatment of stone, gravel and like material, I employ means applied to the gyrating body 10 for receiving the cleaned material and grading, screening or separating the same. To this end, I provide a plurality of screen decks 23 which are preferably disposed below the shaft 13 with the uppermost screen deck in communicating relation with the discharge passage 18 of each scrubbing deck 11, the scrubbed material dropping by gravity onto one end of said uppermost screen deck. In the arrangement of the screens shown in Figures 1 and 2, they are inclined in the direction of length of the body 10 and are of different mesh so that in response to the gyrating action of the machine body, the washed ma-

terial is effectually screened and graded and is discharged from the respective screen decks 23 through suitable discharge openings 24, 25 and 26. As shown in Figure 1, the discharge openings 24 and 25 for the two upper screen decks are located in the end wall 10 of the machine body, while the discharge opening 26 for the lowermost screen may be produced by terminating such screen short of the adjoining body-wall 10.

To prevent the wash water and foreign matter drained through the openings 20 in the bottom of the scrubbing deck 11 from contacting with the cleaned material after its discharge through the openings 18 onto the uppermost screen deck 23, I provide deflecting walls 27 which slope downwardly from a point below the openings 20 to a point substantially centrally of the machine, in the manner shown in Figure 2. By this means the water is directed to a point substantially centrally of the machine and thereupon drains through the respective screen-decks 23 without contacting with the cleaned material.

In the arrangement shown in Figure 3, the screen decks 28 are disposed in sets or groups, one group being disposed beneath each scrubbing deck below its discharge passage 18 and inclined toward the center of the machine in a direction transversely thereof. Each group of screening decks terminates at its inner edges at a point in spaced relation to the opposing edges of the companion group of screening decks, whereby a space is provided for the discharge of the screened material.

In the embodiment of the invention shown in Figure 4, a plurality of transversely inclined screening decks 29 are provided which likewise serve to screen and grade the cleaned material as it is discharged from the scrubbing decks. In this arrangement, a deflecting wall 30 may be provided between the bottom of the scrubbing deck and the uppermost screening deck for directing the wash water discharged from the scrubbing deck to a point centrally of the screen decks 29.

In Figure 5 is shown a still further arrangement of grading decks consisting of an upper deck 31 disposed lengthwise beneath the scrubbing decks 11 and extending from end to end thereof, and lower grading decks 32 disposed beneath the scrubbed material discharge 18 and terminating substantially centrally of the machine-body. A baffle or deflecting wall 33 is disposed between the scrubbing deck 11 and grading deck 31 for diverting the wash water to that part of the latter beyond the inner edges of the lower grading decks 32, whereby the wash water and foreign matter contained therein will not come in contact with the already cleaned material while it is undergoing grading through the decks 31, 32.

I claim as my invention:—

1. A machine for washing and scrubbing gravel and the like, comprising a gyrating body including a substantially trough-shaped scrubbing deck for the material to be treated disposed at one side of its gyrating axis, said deck extending generally in the direction of the body-axis and having openings in its bottom for the discharge of wash-water and foreign matter and a discharge at one end for the washed and scrubbed material, and grading decks for such material mounted on said gyrating body and disposed at the opposite side of its gyrating axis below the scrubbing deck.

2. A machine for washing and scrubbing gravel and the like, comprising a gyrating body including a substantially trough-shaped scrubbing deck for the material to be treated, said deck extending generally in the direction of the body-axis at one side thereof and having openings in its bottom for the discharge of wash-water and foreign matter and a discharge at one end for the washed and scrubbed material, means in said deck for baffling the flow of material therethrough and causing it to take a spiral, tumbling-like course from the feed end toward the discharge end of the deck, and screening decks mounted on said gyrating body at the opposite side of its gyrating axis and below the scrubbing deck for receiving the scrubbed material and grading the same.

3. A machine for washing and scrubbing gravel and the like, comprising a gyrating body including a substantially trough-shaped scrubbing deck for the material to be treated, said deck extending generally in the direction of the body-axis above the same and having openings in its bottom for the discharge of wash-water and foreign matter and a discharge at one end for the washed and scrubbed material, and a plurality of grading decks for such material mounted on said gyrating body below its gyrating axis in substantially balanced relation to the scrubbing deck, the uppermost grading deck being in communicating relation with the scrubbed material discharge of said scrubbing deck.

4. A machine for washing and scrubbing gravel and the like, comprising a gyrating body including a substantially trough-shaped scrubbing deck for the material to be treated, said deck extending generally in the direction of the body-axis at one side thereof and having openings in its bottom for the discharge of wash-water and foreign matter and a discharge at one end for the washed and scrubbed material, and grading decks mounted on said gyrating body at the opposite side of its gyrating axis in substantially balanced relation to the scrubbing deck and in communicating relation with the scrubbed material discharge of said scrubbing deck and inclined to the horizontal to effect the gravity flow of the scrubbed and graded material thereover.

5. A machine for washing and scrubbing gravel and the like, comprising a gyrating body including a substantially trough-shaped scrubbing deck for the material to be treated, said deck extending generally in the direction of the body axis at one side thereof and having openings in its bottom for the discharge of wash-water and foreign matter and a discharge at one end for the washed and scrubbed material, grading decks for such material mounted on said body and disposed below the scrubbing deck at the opposite side of the gyrating axis of such body, and means disposed beneath the wash-water discharge openings for diverting such water at a point remote from the point of discharge of the scrubbed material.

6. A machine for washing and scrubbing gravel and the like, comprising a gyrating body including a substantially trough-shaped scrubbing deck for the material to be treated, said deck extending generally in the direction of the body-axis and having openings in its bottom for the discharge of wash-water and foreign matter and a discharge at one end for the washed and scrubbed material, grading decks

- for such material disposed below the scrubbing deck, and a wash-water deflecting wall disposed beneath the corresponding discharge openings of the scrubbing deck and above said 5 grading decks for diverting such water from the normal discharge path of the scrubbed material, said wall terminating at one end short of the discharge for the scrubbed material.
7. A machine for washing and scrubbing 10 gravel and the like, comprising a gyrating body including a scrubbing deck for the material to be treated, said deck having openings along its bottom for the discharge of wash-water and foreign matter and a discharge at one end for the washed and scrubbed material, a series of grading decks disposed in superposed relation below the scrubbing deck, the uppermost grading deck having one portion thereof in direct communication with the scrubbed material discharge, and a baffle wall overlying such portion of the uppermost grading deck at one side of said last-named discharge for intercepting and directing the discharged wash-water and 10 foreign matter toward the remaining portion of said uppermost grading deck.

WILLIAM L. WETTLAUFER.
